MULTIPLE VALVE SPRING DEPRESSOR

Allen J. Delehanty, Kalamazoo, Mich., assignor
to Borroughs Tool and Equipment Company,
Kalamazoo, Mich., a corporation of Michigan

Application March 19, 1949, Serial No. 82,346

2 Claims. (Cl. 29—216)

1

This invention relates in general to a valve spring depressor and more particularly to a type thereof for simultaneously depressing a plurality of valve springs against the head of an internal combustion engine having overhead valves.

Automobile mechanics familiar with engines having overhead valves are acquainted with the troublesome and time consuming aspects of compressing the valve springs against the engine head in order to position valve keepers around the end of the valve stem for holding said valve springs under compression. According to presently known means and methods, each valve spring must be individually and independently depressed thereby creating a slow and tedious job, especially on engines having eight or more cylinders and, consequently, sixteen or more valves.

There has been a long felt need for a device whereby all the valve springs in a single bank, such as along one head of a V-type, valve-in-head engine, may be depressed by a single operation. To my knowledge, no such device has been created prior hereto.

Therefore, a primary object of this invention is the provision of a device for depressing a plurality of aligned valve springs against an engine head, each spring encircling a valve stem mounted in said engine head.

A further object of this invention is the provision of a multiple valve depressing device, as aforesaid, having means for holding said engine head in a predetermined position with respect thereto, and having additional means for holding said valve in the closed position while said valve spring is being depressed.

A further object of this invention is the provision of a multiple valve depressing device, as aforesaid, in which that portion of said depressing device engaging the valve spring during the depressing operation moves along a line substantially parallel to the axis of the valve stem during the spring depressing operation.

Other objects and purposes of this invention will become apparent to persons familiar with this type of equipment upon referring to the accompanying drawings and upon reading the following specification.

In meeting those objects and purposes heretofore mentioned as well as others incidental thereto and associated therewith, I have provided a multiple valve spring depressing device having a substantially rectangular base, a pair of spaced, preferably parallel, upwardly extending arms secured at their lower ends to said base, and a substantially rectangular rocker platform pivot-

ally supported upon and between the upper ends of the said support arms. A substantially vertical adjustment screw is pivotally and rotatably secured at its lower end upon the said base and is threadedly engaged intermediate its extremities by a corresponding end of the rocker platform, whereby rotation of said screw will affect a tilting of the platform with respect to the base. That end of the rocker platform remote from the end engaged by said screw is provided with a channel shaped spring depressing bar having a plurality of aligned openings therethrough. The channel-shaped bar is positioned so that it opens downwardly. The openings through the channel bar are so disposed therealong that the ends of the valve stems whose springs are being depressed may extend upwardly through said openings as the said bar is lowered. Means is provided on said base and said upwardly extending arms for positioning an engine head upon said base.

For illustrations of a preferred embodiment of my invention attention is directed to the accompanying drawings in which:

Figure 1 is an oblique view of the multiple valve spring depressor to which this invention relates.

Figure 2 is a front elevation view of said device with a valve positioning plate supported upon the base thereof.

Figure 3 is a broken, sectional view taken along the line III—III of Figure 2, including a broken line view of an automobile engine head positioned on the base thereof.

Figure 4 is a broken, sectional view taken along the line IV—IV of Figure 2.

Figure 5 is a top plan view of the multiple valve spring depressor.

Figure 6 is a sectional view taken along the line VI—VI of Figure 5, and includes a cross-sectional view of an automobile engine head positioned upon the base of said valve spring depressor.

Figure 7 is a broken, sectional view taken along the line VI—VI of Figure 5, but showing the rocker platform in a different position than that shown in Figure 6 and including only a broken portion of the said engine head.

Construction

The multiple valve spring depressing device 10 (Figures 1, 2, 3, and 5), hereinafter referred to as the valve spring depressor, is comprised of a rectangular base 11, a pair of spaced, upwardly extending support arms 12 and 13, secured at their lower ends upon said base and pivotally supporting at and between their upper ends a rectangular rocker platform 14.

For the purpose of convenience in description, the terms "front" or "forwardly" and "rear" or "rearwardly," as used in the following specification, will be understood to refer to the rightwardly and leftwardly ends of the device, or parts thereof, when positioned as appearing in Figure 3. The terms "upper" or "upwardly" and "lower" or "downwardly" shall be understood to refer to the device when positioned and/or operating in its normal manner of use.

The base 11 may be made in any appropriate fashion and from any suitable material. However, in this embodiment of the invention said base is fabricated in a rectangular shape from steel bar stock thereby providing the front end bar 15, the rear end bar 16 and the side bars 17 and 18. These said bars may be secured to each other by any suitable means, such as welding, and are preferably positioned on edge. A cross bar 21, which extends between and is secured to the side bars 17 and 18, is parallel with and preferably spaced about 2 inches from the rear end bar 16 in this embodiment of the invention. A pair of parallel bearing plates 22 and 23, which are secured as by welding between the rear end bar 16 and the cross bar 21 are about 2 inches apart and preferably centrally disposed between the side bars 17 and 18. The purpose of the bearing plates 22 and 23 will be described in detail hereinafter. A center bar 24, which extends between and is secured to the cross bar 21 and the front end bar 15, as by welding, is disposed approximately midway between the side bars 17 and 18 and substantially parallel therewith.

It will be clearly understood that the specific dimensions hereinabove or hereinafter disclosed are for illustrative purposes only and are not intended to limit the scope of the invention.

The support arms 12 and 13, which are preferably, but not necessarily, substantially identical, are each comprised of a pair of inner and outer support bars 25 and 26, and 25a and 26a, respectively (Figures 2, 4 and 5). Since, in this embodiment of the invention, said support arms are identical, a detail description will be given herein of the support arm 12, which description is intended to apply substantially to the support arm 13.

The inner and outer support bars 25 and 26 of the support arm 12 are secured at their lower ends, as by welding, to opposite sides of the side bar 17 approximately one inch from the cross bar 21. Said support bars 25 and 26 are preferably inclined toward the forward end of the base 11 at such an angle that they are approximately parallel with the axes of the valve stems when the engine head is supported on the base 11. Thus, in the embodiment here illustrated, the said support bars are disposed at an angle of 15 degrees to the vertical. A spacer 29 is provided between the support bars 25 and 26 near the upper ends thereof for purposes of strength. The upper ends of the support bars 25, 26, 25a and 26a are provided with appropriate coaxial openings through which the pivot pins 31 and 32 (Figures 1 and 5) may extend. Appropriate spring clips 33 are provided to hold the pivot pins 31 and 32 in proper position.

As hereinabove stated the support arm 13 is parallel with the support arm 12 and also spaced approximately one inch from the cross bar 21.

The rocker platform 14 (Figures 1 and 5) has a rear end bar 34 and a pair of side bars 35 and 36 secured to said end bar 34, as by welding. The side bars 35 and 36 are pivotally supported, re-

spectively, at points equidistant from the rear end bar 34 upon the support arms 12 and 13 so that when said side bars 35 and 36 are substantially parallel with the side bars 17 and 18 of the base 11, the rear end bar 34 of the platform is approximately directly above the rear end bar 16 of the base 11. The side bars 17 and 18 of the base 11 preferably extend forwardly of the support arms 12 and 13 farther than the side bars 35 and 36 of the platform 14.

A cross bar 37, which extends between and is secured to the side bars 35 and 36, as by welding, is parallel with and spaced approximately two inches from the rear end bar 34. A pair of parallel bearing plates 38 and 39 (Figure 5) which are secured, as by welding, between the rear end bar 34 and cross bar 37, are approximately 2 inches apart and preferably centrally disposed between the side bars 35 and 36. The purpose of the bearing plates 38 and 39 will be disclosed in detail hereinafter.

A downwardly facing, valve spring engaging channel member 41 (Figures 1, 2, 3 and 5) having a web 42 is secured to the platform side bars 35 and 36 at the ends thereof remote from the rear end bar 34 so that the web 42 is in a plane substantially parallel with that of the side bars 35 and 36. The side bars 35 and 36 may be notched, as shown in Figures 6 and 7, so that the web 42 is positioned approximately midway between the upper and lower edges of said side bars. A center bar 43 which is also provided with a notch for engaging the channel member 41 near one end thereof is secured at its other end to the cross bar 37, as by welding, and is preferably parallel with and substantially equidistant from the side bars 35 and 36.

A pair of brace bars 44 and 45 (Figure 5) are secured to the side bars 35 and 36, as by welding, and extend outwardly and then forwardly therefrom, where they are secured to the opposite outer ends of the channel member 41 for the purpose of imparting better rigidity thereto. The brace bars 44 and 45 are preferably notched, like the side bars 35 and 36, for engaging the channel member 41. The web 42 is provided with a plurality of spaced, aligned, valve stem openings 46 which are preferably elongated along the axis of the web.

A horizontal, cylindrical pivot post 47 (Figures 3 and 4) is rotatably supported within appropriate openings in the bearing plates 22 and 23 and is held in position with respect thereto by means of the spring clips 48. The pivot post 47 (Figure 3) is preferably flattened on two diametrically opposed sides approximately midway between its axial extremities, and a cylindrical opening 49 is provided through said pivot post about midway between the ends thereof and perpendicular to said opposed flat surfaces. A pair of washers 51 and 51a are provided adjacent to said flat surfaces surrounding the opposite ends of the cylindrical opening 49. The lower end of an adjustment screw 52 extends through the washers 51 and 51a, and the cylindrical opening 49. A spring clip 53 is secured to the lower end of the adjustment screw 52 adjacent to the washer 51a and thereby prevents the disengagement of the adjustment screw 52 from the pivot post 47. Thus, the lower end of the adjustment screw 52 is rotatably supported within the cylindrical opening in the pivot post 47, which post in turn is pivotally supported upon the bearing plates 22 and 23.

A horizontal adjustment post 54 (Figures 3 and 5) is rotatably supported within appropriate,

aligned coaxial openings in the bearing plates 38 and 39. A pair of spring clips 55 secured upon the adjustment post 54, adjacent to the opposite axial ends thereof, prevent the accidental removal of the adjustment post 54 from said bearing plates 38 and 39. A diametrically disposed, threaded opening 56 is provided through the adjustment post 54 approximately midway between the axial extremities thereof. The adjustment screw 52 is threadedly engaged by and extends through said threaded opening 56 in the adjustment post 54.

Accordingly, rotation of the adjustment screw 52 in one direction effects an upward movement of the adjustment post 54 with respect to the pivot post 47 and a rotation of the adjustment screw in the opposite direction effects a downward movement of the said adjustment post, thereby controlling the tilting of the platform 14 with respect to the base 11 around the pivot pins 31 and 32. A screw actuating rod 57 is slidably received through an appropriate opening 58 through the upper end of the adjustment screw 52.

A rectangular, valve positioning plate 61 (Figures 2, 3, 4 and 6), having an integral, perpendicularly disposed, plate positioning flange 62 along one lengthwise edge thereof, is removably supportable upon the front end of the base 11 adjacent to the support arms 12 and 13. A plurality of spaced, valve positioning angles 63 are disposed along a straight line on the positioning plate 61 and secured thereto, as by welding, on the side thereof from which the flange 62 extends. The angles 63 are preferably spaced from the flange 62 so that said angles engage the valve heads 64 and hold them firmly closed when the flange 62 bears against the rearward side 60 of the head 28.

A head positioning bar 65 extends between and is secured to the inner support bars 25 and 25a of the support arms 12 and 13, as by welding, so that said bar 65 is substantially parallel with the cross bar 21 and approximately one inch above the base 11. A plurality, here two, of head positioning bolts 66 are threadedly supported in appropriate threaded openings through the positioning bar 65, the leading ends 67 of said bolts 66 extending toward the front end of the base 11. Lock nuts 68 are provided on the bolts 66 for securing them in predetermined position with respect to the bar 65. If the head positioning bolts 66 are in their proper positions and the side 60 of the engine head 28 is placed firmly against the bolt leading ends 67, the upper ends of the valve stems 27 will extend through the valve stem openings 46 in the channel member 41 when the channel member 41 is urged downwardly to compress the valve springs 69 against the upper surface 71 of the engine head 28. When the valve springs 69 are thus depressed, the upper ends of the valve stems 27, including the valve keepers 72, are completely exposed above the web 42 and said keepers can be positioned around or removed from engagement with each valve stem and the retainer ring 73 encircling the upper end of said valve stem 27.

It will be recognized that the present invention may be adapted for use with many types of engine constructions and the particular one herein shown is selected for illustrative purposes only and is not intended to limit the scope of the invention.

As shown in Figure 5, parts trays 14, such as for holding valve keepers, valve springs and other

similar parts, may be supported upon the rocker platform in the spaces provided between the platform side bars 35 and 36 and the platform center bar 43.

Operation

In order to operate the multiple valve spring depressor 10, to which this invention relates, the adjustment screw 52 is rotated in such a direction that the front end of the rocker platform 14, including the channel member 41, is raised high enough to permit placement of the engine head 28 between the channel member 41 and the forward end of the base 11. The valve positioning plate 61 is placed upon the forward end of the base 11 so that the plate positioning flange 62, thereof, is near the lower ends of the support arms 12 and 13 and so that the lengthwise ends of the said positioning plate 61 extend outwardly about equidistantly from the base side bars 17 and 18. The engine head 28 is then placed upon the valve positioning plate 61 and urged rearwardly until the rearward side 60 thereof bears against the leading ends 67 of the head positioning bolts 66 with the valve stems 27 inclined forwardly. The positioning bolts 66 may be adjusted so that the axes of the valve stems 27 are tangent to the arc A (Figure 6) through which the centerline of the valve stem openings 46 swings as the rocker platform 14 is tilted upwardly and downwardly. After the positioning bolts are properly set, as aforesaid, for a particular head, such as the head 28, further adjustment of said bolts is normally not required as long as the depressor 10 is used for depressing valve springs on similar heads. When said valve stem openings 46 are thus properly aligned with the upper ends of the valve stems 27 in said engine head 28, the plate positioning flange 62 is urged tightly against the rearward side 60 of the head 28, thus causing the valve angles 63 to press the valve heads 64 snugly against their seats in the engine head 28 and thereby preventing any material movement of the valve stems 27 while the valve springs 69 are being depressed.

When the engine head 28 is properly positioned upon the base 11 as above described, the adjustment screw 52 is then rotated by means of the actuating rod 57 until the channel member 41 engages the upper end of the valve spring 69, as shown in Figure 7, and then depresses said valve spring to a position as shown in Figure 6. The valve keepers 72 are placed in position around the upper end of each valve stem 27, as shown in Figure 6, and the adjustment screw 52 is counter rotated, thereby releasing the compression of the spring 69 until the keepers 72 rest snugly within the upper valve spring thimble 70. Thus the valve spring 69 is held under compression between the valve keepers 72 and the engine head upper surface 71, in a conventional manner. A continued counterrotation of the adjustment screw 52 will raise the channel member 41 to the position necessary for removing the engine head 28 from upon the base 11.

It will be recognized that the above described procedure for positioning valve keepers may be employed in reverse in removing valve keepers from the valve stem.

It has been found advantageous to provide support arms 12 and 13 extending sufficiently above the base 11 that the axis of the stem 27 (Figure 6), when the engine head 28 is properly positioned upon the base 11, is tangent to the arc A at a point thereon midway between the upper and

lower extremities of the spring depressing stroke, or approximately midway between the positions of the channel member as shown in Figures 6 and 7, respectively. Thus, the travel of the channel member 41 during the depression of the valve spring 69, and the force resulting therefrom, are substantially parallel with the axes of the valve stems 27.

It will also be noted that the adjustment screw 52 must be of sufficient length to permit a lowering of the forward end of the rocker platform 14 so that complete and adequate depression of the valve springs 69 may be effected. Accordingly, it will be seen that the length of the support arms 12 and 13, the distance between the pivot pins 31 and 32 and the said centerline of the valve stem openings 46 in the web 42, and the length of the adjustment screw 52 are interdependent and critical to the proper and satisfactory operation of the multiple valve spring depressor 10.

Although the above mentioned drawings and description apply to one particular, preferred embodiment of the invention, it is not my intention, implied or otherwise, to eliminate other variations or modifications which do not depart from the scope of the invention unless specifically stated to the contrary in the hereinafter appended claims.

I claim:

1. In a device for depressing a plurality of valve springs, each encircling a valve stem mounted in an engine head, while holding said valve stem in a fixed position, the combination comprising: a base having opposite ends; a pair of parallel, spaced support arms secured to and extending upwardly from said base intermediate the ends thereof; a rocker platform having opposite ends, said platform being pivotally supported at points intermediate said platform ends upon the upper ends of said support arms; an adjustment screw pivotally and rotatably supported at one end upon said base near one end thereof, and threadedly and pivotally engaged intermediate its ends by the corresponding end of said platform, whereby rotation of said screw effects a tilting of said platform; an elongated plate secured to that end of said platform remote from said screw, said plate being positioned over the corresponding end of said base and having a plurality of openings therethrough and arranged along a line thereon; and means positioning said head on said base in a predetermined relation therewith; said platform pivot points being so spaced from said base and said screw being of such length that actuation of said screw will cause said line on said plate to pass through an arc, the midpoint of which is tangent to the axes of said valve stems and the ends of which constitute, respectively,

the beginning and end of a spring depressing operation of said device.

2. In a device for depressing a plurality of valve springs, each encircling a valve stem mounted in an engine head, the combination comprising: a rectangular base having a horizontal pivot post rotatably supported thereon parallel with and adjacent to one end thereof; a pair of parallel, spaced support arms secured to and extending upwardly from said base at points spaced inwardly and equidistantly from the axis of said pivot post; a rectangular rocker platform pivotally supported at points spaced equidistantly from one end thereof upon the upper ends of said arms; a horizontal adjustment post pivotally supported upon said platform intermediate said one end thereof and a line between said points thereon, said adjustment post being substantially directly above said pivot post when said base and said platform are parallel; an adjustment screw having one end rotatably secured to said pivot post, and being threadedly engaged by said adjustment post intermediate its ends whereby rotation of said screw effects a tilting of said platform; a channel shaped member having a web secured to that end of said platform remote from said adjustment post, said channel member opening downwardly toward the corresponding end of said base, and said web being substantially parallel with said platform and having a plurality of openings therethrough and arranged along the longitudinal centerline thereof; means removably supportable upon said base holding said valve stems in a fixed position with respect to said head and means positioning said head on said base in a predetermined relation therewith; said platform pivot points being so spaced from said base and said screw being of such length that actuation of said screw will cause said web centerline to pass through an arc, the mid-point of which is tangent to the axes of said valve stems and the ends of which constitute, respectively, the beginning and end of a spring depressing stroke of said web.
